UNITED STATES PATENT OFFICE

DOLA TYLER AND THOMAS B. MERRILL, OF TULSA, OKLAHOMA

TABLE CONSTRUCTION

Application filed April 20, 1929. Serial No. 356,837.

This invention relates to improvements in tables.

The primary object of this invention is the provision of an improved table construction embodying a novel type of collapsible and extensible supporting leg construction which may be extended in such manner as to not interfere with persons seated at the table.

A further object of this invention is the provision of a table construction of a relatively long type, including collapsible leg constructions at the end thereof with novel means to maintain the same extended or collapsed in a non-obstructing relation with persons or guests seated at the table.

Other objects and advantages of this invention will be apparent during the course of the following detailed description.

In the accompanying drawings, forming a part of this specification, and wherein similar reference characters designate corresponding parts throughout the several views,

Figure 1 is a longitudinal sectional view taken thru the improved table construction in an extended position for use.

Figure 2 is a transverse sectional view taken thru the table construction showing its legs in end elevation.

Figure 3 is a bottom plan view of the table with the legs extended.

Figures 4 and 5 are sectional views taken substantially on their respective lines in Figure 1 of the drawings.

Figure 6 is a bottom plan view of the table collapsed.

Figure 7 is a sectional view taken substantially on the line 7—7 of Figure 6.

Figure 8 is an enlarged fragmentary sectional view taken thru details of the leg construction.

Figure 9 is a fragmentary perspective view of the upper end of one of the leg constructions of the table.

Figure 10 is a perspective view of a brace member used in connection with the leg structure of the table.

Figure 11 is a sectional view taken substantially on the line 11—11 of Figure 2.

In the drawings, wherein for the purpose of illustration is shown only a preferred em-

bodiment of the invention, the letter A may generally designate the improved table, which includes a top construction B, having collapsible leg constructions C at each end thereof, with means D to support the same extended or collapsed.

Referring to the table top construction B, the same includes a table board or top 15 having oppositely disposed longitudinal side flanges 18 and 19 which may be held in a right angled depending relation with respect to the table top 15, by means of triangular shaped blocks 20 suitably attached in position at the inside of the various flanges to the table top 15 beneath the same.

The leg constructions C are identical and are best illustrated in Figures 8 and 9 of the drawings. Each of the same comprises a pivoted device 25, which is pivoted, as will be subsequently described, on the bottom surface of the table top 15, and includes the elongated cross piece 26 adapted to extend transversely across the table top 15, beneath the same, and which is morticed at 27 inwardly of the top surface thereof, and wherein the

leaves 28 of hinges are suitably secured; the other leaves 29 of the hinges being adapted to be secured to a cross rail 30 which is nailed or otherwise affixed beneath the top wall 15, at each end of the table, in right angled relation with its longitudinal axis, at a predetermined distance inwardly from each of the end depending flanges 16 and 17.

The pivoted device 25 in addition to the cross piece 26 includes the depending leg supporting member 35, which has a morticed connection in the cross piece 26, preferably being provided with the upstanding shanks 36, adapted to be received within suitable recesses 37 provided as sockets thru the cross piece 26,

as is illustrated in Figures 8 and 9 of the drawings. The depending member 35 is of the same width as the cross piece 26, but in width it is considerably less than the width of the cross piece 26, and together with the cross piece 26 forms a T-shaped arrangement as the pivot device 25. Inwardly of its lower edge 40 the member 35 is upwardly recessed at 41 and wherein an end of a brace arm 45 is pivoted as will be subsequently described. In-

wardly of the opposite sides thereof the depending attaching shank 35 of the pivoted device 25 is morticed, at 46, on an incline or bevel; the mortice recesses 46 being inclined in a divergent relation with respect to each other away from the hinged end of the T-shaped pivoted device 25; the said mortice recesses 46 opening at opposite sides of the member 35 and extending to the outer free edge 40. In the mortice recesses 46 tenons 54 of the supporting legs 50 and 51 of each leg construction C are connected, snugly fitting in the mortice recesses 46, so that the legs 50 and 51 are in a divergent relation at their lower ends.

15 To hold the mortice and tenon connections of the legs 50 and 51, a horizontally disposed attaching bolt 60 is threaded thru suitable aligning apertures in the upper ends of the legs and the member 35, as is illustrated in the drawings, the outer side of one of the legs 50 being recessed to receive the head of the bolt 60 and the opposite side of the leg 51 being recessed to receive the nut of the bolt; the 20 horizontal bolt 60 extending transversely across the width of the shank or member 35 of the pivoted device 25, and intersecting the slot 41, to act as a pivot member for pivoting the apertured end 65 of the brace arm 45 thereto.

25 A noteworthy feature of the invention is the fact that the cross piece 26 and the depending attaching member 35 of the T-shaped pivoted device 25, as well as the legs 30 50 and 51 supported thereby, are all of the same thickness and hingedly supported and attached together in the same plane. The thickness of this leg construction C is relatively shallow, so that it does not occupy much 35 space beneath the table, and the upper ends of the legs 50 and 51 are rigidly secured to the relatively narrow member 35 in a close 40 proximate relation, and diverge towards their outer ends, so that persons at opposite sides 45 of the table may sit comfortably, notwithstanding the legs which support the table, as 50 they are so designed as to be located in an unobstructed relation with respect to persons seated at the table, as can be readily understood from Figure 2 of the drawings.

55 The hinges secure the cross piece 26 of each of the pivoted devices 25 to the cross rails 30, beneath the table top, at locations laterally of the leg attaching member or shank 35, and thus the leg constructions are durably and efficiently pivoted to the table top structure against liability of wobbling.

60 Referring to the means E for securing each leg construction C collapsed or extended, the same are identical for each leg construction, and in this connection a cross brace 70 is secured beneath the table top 15 substantially midway intermediate the ends thereof, in a depending relation. At each side of this cross brace or rail 70 are a pair of spaced brace at-

70 taching flanges 72 and 73, in a spaced relation to provide a channel 74 therebetween, at each side of the cross rail 70. These flanges 72 and 73 are reinforced and secured to the cross rail 70 by triangular shaped blocks 75 which are suitably nailed or otherwise secured in the corners at the juncture of the ends of the flanges 72 and 73. Each passageway or space 75 74 located at the longitudinal axis of the table is closed at the rail 70, but open at the opposite ends of the flanges 72 and 73. At the cross rail 70 the flanges 72 and 73 are provided with aligning openings 77, and in further spaced relation transversely aligning openings 78. Referring now to the diagonal brace arm 45 for each of the leg constructions as above mentioned, the end of the same is pivoted to each of the leg constructions and more particularly the pivoted device 25, in a spaced relation with respect to the pivot axis of the device 25. The opposite end of the brace arm construction 45 may be enlarged and is provided with a transverse opening 80, thru which a tapered dowel pin 81 may be inserted, for the purpose of locking the arm. When the leg construction C is extended the brace arm 45 will be diagonally arranged, with its free moving end extending into the space or channel 74 between the flanges 72 and 73, and it is secured in such relation by means of the dowel pin 81 which is threaded, as shown in Figure 1, thru the openings 78, and the opening 80 of the brace arm. Additional reinforcement may be provided for holding this end of the diagonal brace arm 45 in position, in the nature of a recess 85 provided inwardly of a bevel edge 86 of the brace arm 45; the bevel edge 86 resting against the under surface of the table top 15, and a stop piece 87 being rigidly affixed to the table top 15 in an intersecting relation across the passageway or channel 74, which is received in the recess 85.

65 In the event of collapsing the table legs, the dowel pins 81 must of course be removed and the brace arm 45 is knocked from retained position on the stop piece 87, and the brace arm 45 is then slid longitudinally along the channel 74 into its collapsed position in said channel, as illustrated in Figure 6 of the drawings, and the leg construction C is then folded substantially flat beneath the top 15, it being noted that the edge 40 of the pivoted portion 25 is slightly spaced from the extreme outer end of the flanges 72 and 73, to 120 permit the leg constructions C to collapse substantially flat beneath the top 15, with the legs 50 and 51 divergent at either side of the flanges 72 and 73. In this position the apertures 65 align with the transverse apertures 77 to receive the dowel pins 81 for the purpose of holding the legs collapsed in the relation illustrated in Figure 6 of the drawings.

70 From the foregoing description of this in-

vention it is apparent that a novel type of table construction has been provided, which may efficiently serve the purpose of providing a table, the legs of which may be extended or collapsed as desired. The fact that the legs are collapsible does not interfere with the bulk of the same, since due to the compact and efficient arrangement of the leg construction, they may be extended or collapsed into a very compact relation; the leg constructions when extended do not interfere with the guests seated at the table in any manner whatsoever, and because of this feature the table construction has been particularly designed for use at banquets where relatively long tables are provided, which may be collapsed for purposes of portability, and which may be extended into a very stable and durable relation due to the novel design and reinforced bracing features of the leg construction.

Various changes in the shape, size, and arrangement of parts may be made to the form of invention herein shown and described, without departing from the spirit of the invention or the scope of the claims.

We claim:

1. In a table construction the combination of an elongated table top, a leg construction pivoted to the table top at each end thereof, a pair of spaced flanges beneath the table top providing a channel, a brace arm pivotally connected at one end to each of the leg constructions having a width substantially equal to the width of the channel and slidable therein, locking means associated with said flanges and said brace arms locking the brace arms in various positions for supporting the leg constructions extended or collapsed with respect to the table top, said leg constructions and brace arms bearing such relation to the length of the table and channel that when the leg constructions are collapsed the brace arms will lie in the channels in aligning relation.

2. In a table construction the combination of a table top, a substantially T-shaped device including a cross piece and a reduced depending shank in right angled relation between the ends of the cross piece, means pivoting the cross piece to the table top, said depending shank having its opposite sides thereof morticed in a divergent relation, a pair of supporting legs having their proximate ends in said divergently morticed recesses, means securing the adjacent ends of the legs in a rigid relation with the shank so that the legs are divergent from the shank, the cross piece, shank and legs all being of the same thickness and lying in the same plane, and means for supporting the shank in a collapsed substantially flat relation beneath the table top or extended in right angled relation with respect to the table top.

3. In a table construction the combination

of a table top, a substantially T-shaped device pivoted beneath the table top having a recess extending from the outer edge thereof towards the pivoted end thereof, legs, bolt means detachably connecting said legs to the T-shaped device with the bolt means extending transversely thru said recess, a brace bar pivoted on the bolt means in said recess, and means for holding the bar in any of several positions with respect to the table top for holding said legs collapsed or extended with respect to the table top.
